BASE FOR TABLE LEG OR LIKE SUPPORT STRUCTURE

Irvin Hollander, Dayton, Ohio, assignor to TiiDee Products Co., Dayton, Ohio

Filed Dec. 5, 1969, Ser. No. 20,373

Term of patent 14 years

Int. Cl. D8—09

U.S. Cl. D8—235

FIG. 1 is a top perspective view of a base for table leg or like support structure embodying my design;
FIG. 2 is a top view thereof;
FIG. 3 is a side elevation view thereof;
FIG. 4 is a bottom perspective view thereof;
FIG. 5 is a bottom plan view thereof; and
FIG. 6 is a bottom perspective view illustrating a slight modification of my design wherein the outer periphery thereof is circular rather than rectangular as illustrated in FIGS. 1 through 5.

I claim:

The ornamental design for a base for table leg or like support structure, substantially as shown and described.
